(57) **CLAIM**

The ornamental design for a pill container, as shown and described.

DESCRIPTION

FIG. 1 is a top, front, side perspective view of a pill container showing my design therefor;

FIG. 2 is a bottom, rear, opposite side thereof;

FIG. 3 is a front elevational view thereof, the sides and rear being the same;

FIG. 4 is a sectional view taken along line 4-4 of FIG. 3 for the purpose of showing the contour of the lower recess, the broken lines indicating environment and forming no part of the design

FIG. 5 is a top plan view thereof;

FIG. 6 is a bottom plan view thereof; and,

FIG. 7 is a side elevational view of an alternate embodiment with all other views being the same as the embodiments of FIGS. 1-6. thereof.
